[57] CLAIM

The ornamental design for a roller skate, as shown and described.

DESCRIPTION

FIG. 1 is a perspective view of a roller skate showing our new design;
FIG. 2 is a side elevational view thereof;
FIG. 3 is a top plan view thereof;
FIG. 4 is a front elevational view thereof;
FIG. 5 is a rear elevational view thereof;
FIG. 6 is a bottom plan view thereof;
FIG. 7 is another top plan view thereof showing the design in an adjusted condition;
FIG. 8 is a side elevational view thereof; and
FIG. 9 is a bottom plan view thereof.

*Fig. 1**Fig. 2*

*Fig. 3.**Fig. 4.**Fig. 5.**Fig. 6.**Fig. 7.**Fig. 8.**Fig. 9.*
